UNITED STATES PATENT OFFICE

118,389

DESIGN FOR A STORAGE BATTERY BOX

Arthur G. Phelps, Anderson, Ind., and Frederick G. Stickel, Detroit, Mich., assignors to General Motors Corporation, Detroit, Mich., a corporation of Delaware

Application October 9, 1939, Serial No. 87,593

Term of patent 7 years

To all whom it may concern:

Be it known that we, Arthur G. Phelps and Frederick G. Stickel, citizens of the United States, residing at Anderson, in the county of Madison and State of Indiana, and Detroit, in the county of Wayne and State of Michigan, respectively, have invented a new, original, and ornamental Design for a Storage Battery Box, of which the following is a specification, reference being had to the accompanying drawing, forming part thereof.

In the drawing:

Fig. 1 is a side view of a storage battery box showing our new design.

Fig. 2 is an end view thereof.

The end of the battery box not visible is identical with the end that is shown and the rear of the box is identical with the front with the exception that the circular shield is omitted, the bands being of uniform width. The top of the battery box is conventional.

We claim:

The ornamental design for a storage battery box, as shown and described.

ARTHUR G. PHELPS.
FREDERICK G. STICKEL.
